(57) **CLAIM**

The ornamental design for a medical imaging stand, as shown and described.

DESCRIPTION

FIG. 1 is a front view of a first embodiment of a medical imaging stand showing our new design;

FIG. 2 is a back elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view taken generally from the upper, front, left-hand side thereof;

FIG. 8 is a perspective view taken generally from the upper, back, right-hand side thereof; and

FIG. 9 is a perspective view taken generally from the upper, front, left-hand side thereof with the bucky rotated to a horizontal position and in an alternative vertical position along the stand.

FIG. 10 is a front view of a second embodiment of the medical imaging stand with an extended support arm;

FIG. 11 is a back elevational view thereof;

FIG. 12 is a top plan view thereof;

FIG. 13 is a bottom plan view thereof;

FIG. 14 is a right side elevational view thereof;

FIG. 15 is a left side elevational view thereof;

FIG. 16 is a perspective view taken generally from the upper, front, left-hand side thereof;

FIG. 17 is a perspective view taken generally from the upper, back, right-hand side thereof; and,

FIG. 18 is a perspective view taken generally from the upper, front, left-hand side thereof with the bucky rotated to a horizontal position and in an alternative vertical position along the stand.

The broken lines shown in the drawings represent portions of the medical imaging stand that form no part of the claimed design.
